(57) **CLAIM**

The ornamental design for a triangular quilted fabric steam pocket for a steam appliance, as shown and described.

DESCRIPTION

FIG. 1 is a top perspective view of a triangular quilted fabric steam pocket for a steam appliance showing our new design; FIG. 2 is a top plan view thereof;

FIG. 3 is a bottom plan view thereof;

FIG. 4 is a rear elevational view thereof;

FIG. 5 is a front elevational view thereof;

FIG. 6 is a right side view thereof;

FIG. 7 is a left side view thereof; and,

FIG. 8 is a front perspective view of the triangular quilted fabric steam pocket of FIG. 1 installed on a steam mop.

The broken line showing of the mop handle and reservoir is included for the purpose of illustrating and forms no part of the claimed design.
